UNITED STATES PATENT OFFICE

FRANK GREENE, OF TORONTO, ONTARIO, CANADA

PRINTER'S CHASE

Application filed February 17, 1928. Serial No. 255,156.

My invention relates to an improved printer's chase, the object being to arrange means for securely locking the type in position, by parts embodied in the construction of the frame, and adapted to the necessary adjustments therefor.

The essential object of the device is to provide means for locking, squaring and centering the type in the frame, by combinational adjusting parts and unattachable therefrom, thus eliminating the use of furniture, quoins and other removable and loose parts as are in present use for squaring and locking the type in the frame.

15 In the drawings; Figure 1 is a plan view of the chase partially in section;

Figure 2 is a detail sectional view on line *a*—*a* Figure 1; and

Figure 3 is a detail perspective view of one 20 corner of the frame.

Similar reference characters are used to indicate similar parts throughout the drawings:

The frame A embodies two corresponding 25 rectangular shaped sections *a* and *a'*, right angled in cross section, and adapted to be securely fastened together into channeled formation, by fastening screws B, or by any other suitable method.

30 Suitably journalled in each of the sides of the frame A, within the channel formation are reciprocal screws C and D, and journalled in each of the ends of the frame are reciprocal screws E and F, each of the screws being centrally divided into right and left turns, for the purpose hereinafter described.

The screws are journalled at each corner of the frame A, in pillow blocks G, formed integral with the frame.

40 Journalled in parallel relation with the screw F is a connecting rod H, and journalled in parallel relation with the screw D is a similar connecting rod I.

Keyed on one end of the screw C is a 45 small bevel pinion *c'*, and keyed on each end of the rod H, are bevel pinions *h* and *h'* respectively.

Keyed on the end of the screw D is a 50 corresponding bevel pinion *d*. The pinions *d* and *h'* are in mesh with one another, but

the pinions *c'* and *h* do not mesh, but are relatively adjacent to jointly engage in mesh with a pinion J, pivotally journalled in the corner of the frame, and formed with a head *j*, which projects out through an opening *j'* formed in the section *a'* of the frame A.

Counter sunk into the head *j* is a square key seat *j*² into which may be fitted an ordinary square pointed key or other instrument to turn or rotate the pinion J.

The pinion J being in mesh with the pinion *c'* of the screw C, and the pinion *h* of the connecting rod H, and the pinion *h'* at the opposite end being in mesh with the pinion *d* of the screw D, are so connected with one another, that by turning or rotating the pinion J, the screws C and D will turn in unison.

K—K designate cross bars forming part 70 of a movable frame adjustably riding one on each half of the screws C and D.

The screws pass through an interiorly screw threaded bore formed in each end of the bars, so that as the screws are being turned in unison, the cross bars K—K, adjust towards or away from one another in exact synchronism, towards or away from the center of the frame.

The movable frame comprises two separate 80 unites of similar parts, and similar in operation, the one for adjusting the cross bars K—K up and down the frame A, and the other for adjusting the longitudinal bars L—L crosswise of the frame.

Pivotally journalled in the corner of the frame diametrically opposite the pinion J is a pinion M, adapted to mesh with and turn the pinions *e* and *i* keyed respectively on the ends of the screws E and the connecting rod I. On the opposite end of the rod I is a small bevel pinion *i'*, in mesh with a pinion *f'* keyed on the end of the screw F.

The pinion M is formed with a head *m'* 95 which projects out through the top section *a'* of the frame A, and is formed with a counter sunk square key seat *m*², into which may be inserted any kind of a suitable key or tool to turn the pinion in either direction,

to rotate the screws E and F in unison, through the connection with the rod I.

The screws E and F pass through interiorly screw threaded bores formed in the 5 ends of the rods or bars L—L so that by turning the screws in either direction the bars L—L will travel on the screws and adjust towards or away from one another in unison, accordingly with the direction in 10 which the pinion M is turned.

To square and lock the type in the chase, the loose type is placed in the center section marked N, formed by the two cross bars K—K and L—L, a key is inserted in the seat 15 j^3 and the pinion is turned in the direction to adjust the bars K—K towards the center of the frame until the adjustment is checked by contacting with the type.

The same adjustment is made to the longitudinal bars L—L, by inserting a key or tool into the seat formed in the head of the pinion M, the pinion is then turned in a direction to cause the bars L—L to travel on the screws E and F towards the center of 20 the frame A until the adjustment is checked by engaging against the sides of the block of type. The type is by this means securely held in the center of the chase.

To release and remove the type from the 30 chase, the respective pinions J and M are turned in the direction to adjust the two sets of screws in directions that will cause the bars K—K and L—L to travel outwardly or towards the sides and ends of 35 the frame.

Slight modifications may be made in the relation to the gears and the method of adjusting them to turn the screws, without deviating from the nature of my invention.

40 What I claim as new and desire to secure by Letters Patent is:—

1. A printer's chase comprising a rectangular frame consisting of two angular sections secured together into channel formation, reciprocal screws journalled in the sides and ends of said frame, cross and longitudinal bars screw mounted on said reciprocal screws, bevel gears keyed on the ends of said screws, a connecting rod mounted in 45 the side of said frame and in gear connection with the reciprocal screws in the ends of the frame, and a connecting rod mounted in the end of the frame and being in gear connection with the reciprocal screws in the 50 sides of the frame, bevel gears journalled in two oppositely opposed angles of said frame, said gears being in mesh with gears keyed respectively on the ends of the reciprocal screws in one direction and the connecting rod in the other direction, key seats 55 formed in the said gears by which the gears may be turned to actuate the respective rods and screws for adjusting the cross and longitudinal bars towards or away from one another, as and for the purpose specified.

2. A printer's chase comprising a rectangular frame consisting of two angular sections secured together into channel formation, reciprocal screw rods journalled in the sides and ends of said frame, bevel gears 70 keyed on the ends of said screw rods, connecting rods having gears keyed on the ends thereof mounted in one side of said frame and engaging in mesh with the gears on the ends of the screw rod journalled in the ends 75 of said frame, and a connecting rod having gears keyed on the ends thereof mounted in one end of said frame, and engaging in mesh with the screw rod journalled in the sides 80 of said frame, whereby by turning either of said rods the screws in mesh therewith will turn in unison, cross and longitudinal bars screw mounted on said screws, the said cross and longitudinal bars being adapted to adjust towards and away from each other by 85 the turning of the said screws, as and for the purpose specified.

Signed at Toronto, this 3d day of February, 1928.

FRANK GREENE.
